(57) **CLAIM**

The ornamental design for a sensor support, as shown and described.

DESCRIPTION

FIG. 1 is a side view of the sensor support design; FIG. 2 is a front view of the design shown in FIG. 1; FIG. 3 is a top view of the design shown in FIG. 1; FIG. 4 is a bottom view of the design shown in FIG. 1; FIG. 5 is a perspective top view of the design shown in FIG. 1;

FIG. 6 is a perspective bottom elevation view of the design shown in FIG. 1; and,

FIG. 7 is an exploded view of the design shown in FIG. 1. In the drawings, the broken lines shown are for illustrative purposes only and depict a portion of the sensor support which form no part of the claim.
